United States Patent Office.

JAMES SWAN, OF SEYMOUR, CONNECTICUT.

Letters Patent No. 78,769, dated June 9, 1868.

IMPROVEMENT IN THE MANUFACTURE OF AUGERS AND BITS.

The Schedule referred to in these Letters Patent and making part of the same.

TO ALL WHOM IT MAY CONCERN:

Be it known that I, JAMES SWAN, of Seymour, in the county of New Haven, and State of Connecticut, have invented a new and useful Improvement in Machinery for Manufacturing Augers and Bits; and I do hereby declare that the following is a full, clear, and exact description thereof, which will enable those skilled in the art to make and use the same, reference being had to the accompanying drawings, forming part of this specification.

This invention relates to a new and improved machine for upsetting the lips of curved or gauge-lip augers and bits.

In manufacturing augers and bits of the above description, it is necessary to leave a sufficient thickness of metal at the bit and to admit of the spur or screw being formed, after which the lips require to be reduced and brought to a knife-like edge at their cutting-parts, which process is termed "upsetting," and has hitherto been mostly done by hand, but the most skillful workman can scarcely obtain a perfect form of cutters, and perfect uniformity in the two lips is rarely ever obtained.

My invention operates well, and performs the work expeditiously, with but very little manipulation on the part of the operator.

In the accompanying sheet of drawings—

Figure 1 is a front view of my invention.

Figure 2, a plan or top view of the lower part of the same, the upper part being removed, as indicated by the line *z z*, fig. 3.

Figure 3, a side sectional view of the same, taken in the line *y y*, fig. 2.

Figure 4, an under or face view of the swaying or drawing-die.

Figure 5, a side view of an auger to be operated upon.

Figure 6, a side view of an auger finished by my invention.

Similar letters of reference indicate corresponding parts.

A A represent two jaws connected at one end by a pivot, *a*, and having dies, B B, inserted in their opposite ends to receive and hold the screw-portion of the auger C while its cutters or lips, *b b*, are being operated upon, the two jaws being brought together and held by a lever, D, as will be fully understood by referring to figs. 1 and 2.

The upper surfaces of the dies B B are grooved or hollowed out to conform to the desired shape of the lips or cutters, as shown at *c c* in fig. 2.

E represents a curved standard, which is attached to one of the jaws of the machine. This standard projects forward, and has a cylindrical socket, G, at its front end, in which a vertical arbor, H, is fitted and allowed to turn and work up and down freely.

On this arbor H, within the socket G, there is fitted a spiral spring, I, the upper end of the spring being attached to the arbor, and the lower end attached to the bottom of the socket, as shown clearly in fig. 3.

This spring I has a tendency to keep the arbor H elevated as high as it is designed to go, and to the lower end of the arbor there is attached a cylindrical hub, *d'*, in which the swaying or drawing-dies J J are fitted, the lower surfaces or faces of which are slightly inclined.

On the upper part of the arbor H there is fitted loosely a bevel-wheel, K, into which a corresponding wheel, L, gears, the latter being on a horizontal shaft, M, the bearings of which are connected to the socket G.

The bevel-wheel K has an upright pin, *d*, attached to it, and a pin, *e*, projects horizontally from the upper part of the arbor H, as shown in fig. 1.

The shaft M has a cam, N, firmly secured upon it, against which the upper end of arbor H is kept in contact by the spring I.

By this arrangement of the cam, spring, and gearing, as shown and described, two motions are given the arbor H, to wit; an up-and-down and a rotary movement, the arbor being depressed or forced downward by the

action of the prominent portion of the cam N, and forced upward by the spring I, when the prominent portion of the cam passes the upper end of the arbor.

The rotary movement is given the arbor when the latter is forced down in consequence of the pin d of the wheel K coming in contact with the pin e of the arbor.

A quarter revolution, however, is only given the arbor H, as, when the arbor is thrown upward, the pin e of the arbor clears the pin d of the wheel K.

The arbor H, in turning the quarter revolution as specified, winds up the spring I, which, as soon as the arbor rises sufficiently to cause the pin e to clear the pin d, throws or turns back the arbor H to its original position, a pin, f, in the hub, d', of the arbor coming in contact with a pin, g, in the under side of the standard E, these pins serving as a stop, (see fig. 1.)

The dies J J, when the arbor H is forced down and turned, act upon the lips or cutters b b of the auger or bit, and draw them out to a thin edge, giving them the proper shape or form.

In fig. 5, b^x represents the thick edges of an unfinished lip or cutter, and b, fig. 6, the finished lip or cutter operated upon by my invention.

I claim as new, and desire to secure by Letters Patent—

1. The rising and falling, and partially-rotating arbor H, provided with the swaying and drawing-dies J J, in combination with the holding-dies B B, all arranged substantially as and for the purpose set forth.

2. The combination of the cam N, bevel-wheels K L, pins d e, arbor H, and the spring I, all arranged to operate the arbor in the manner substantially as and for the purpose set forth.

JAMES SWAN.
